CLAIM

I claim the ornamental design for a cooler lid, as shown and described.

DESCRIPTION

FIG. 1 is a perspective view of the cooler lid of the present invention having a closed access door and a closed tray accessory;

FIG. 2 is a view of the cooler lid of FIG. 1 having an open access door and an open tray accessory; and,

FIG. 3 is a bottom elevational view of the cooler lid of FIG. 1 having an open access door and a closed tray accessory. The broken lines are for illustrative purposes only and form no part of the claimed design.
